Des. 236,389
Patented Aug. 19, 1975

236,389

QUILL BOX

Olin H. Baker, Madison, Ind., assignor to Meese, Inc.

Filed Jan. 14, 1974, Ser. No. 432,960

Term of patent 14 years

Int. Cl. D9—04

U.S. Cl. D87—1 R

Fig. 1

Fig. 2

Fig. 3

Fig. 4

Fig. 5

Fig. 6

FIG. 1 is a top plan view of a quill box, showing my new design.

FIG. 2 is a side elevational view thereof, the opposite side being identical thereto.

FIG. 3 is a bottom plan view.

FIG. 4 is an end elevational view, the opposite end being identical thereto.

FIG. 5 is a section taken at lines 5-5 in FIG. 2.

FIG. 6 is a section taken at lines 6-6 in FIG. 5.

I claim:

The ornamental design for a quill box, as shown and described.
